(57) **CLAIM**

The ornamental design for a dark-out box for agricultural ventilation as shown and described.

DESCRIPTION

FIG. 1 is a front perspective view of the dark-out box for agricultural ventilation;

FIG. 2 is front elevational view of the dark-out box for agricultural ventilation;

FIG. 3 is a rear elevational view of the dark-out box for agricultural ventilation;

FIG. 4 is a right side elevational view of the dark-out box for agricultural ventilation;

FIG. 5 is a left side elevational view of the dark-out box for agricultural ventilation;

FIG. 6 is a top plan view of the dark-out box for agricultural ventilation; and,

FIG. 7 is a bottom plan view of the dark-out box for agricultural ventilation.

1 Claim, 7 Drawing Sheets
